UNITED STATES PATENT OFFICE

155,354

DESIGN FOR A COFFEE WARMER OR SIMILAR ARTICLE

Peter Muller-Munk, Pittsburgh, Pa., assignor to
The Silex Company, Hartford, Conn., a corporation of Connecticut

Application February 17, 1948, Serial No. 144,549

Term of patent 14 years

(Cl. D81—10)

To all whom it may concern:

Be it known that I, Peter Muller-Munk, a citizen of the United States, residing at Pittsburgh, in the county of Allegheny and State of Pennsylvania, have invented a new, original, and ornamental Design for a Coffee Warmer or Similar Article, of which the following is a specification, reference being had to the accompanying drawing, forming part thereof.

Fig. 1 is a top plan view of a coffee warmer or similar article, showing my new design.

Fig. 2 is a side elevational view thereof.

Fig. 3 is a fragmentary side elevational view thereof with parts in section.

Fig. 4 is a fragmentary bottom plan view thereof with parts broken away.

I claim:

The ornamental design for a coffee warmer or similar article, substantially as shown.

PETER MULLER-MUNK.
